UNITED STATES PATENT OFFICE

RAY R. HUTCHESON, OF RICHMOND HILL, NEW YORK, ASSIGNOR TO WM. DEMUTH & CO.,
A CORPORATION OF NEW YORK

DESIGN FOR AN ASH TRAY OR ARTICLE OF ANALOGOUS NATURE

Application filed September 24, 1931. Serial No. 41,202. Term of patent 3½ years.

To all whom it may concern:

Be it known that I, RAY R. HUTCHESON, a citizen of the United States of America, and a resident of Richmond Hill, county of Queens, and State of New York, have invented a new, original, and ornamental Design for Ash Trays or Articles of Analogous Nature, of which the following is a specification, reference being had to the accompanying drawings, forming a part hereof.

In the drawings:

Fig. 1 is a top plan view of the ash tray or article of analogous nature;

Fig. 2 is a front elevational view of the ash tray or article of analogous nature; and

Fig. 3 is a side elevational view of the ash tray or article of analogous nature.

I claim:

The ornamental design for an ash tray or article of analogous nature substantially as shown.

RAY R. HUTCHESON.
